UNITED STATES PATENT OFFICE.

WILLIAM N. BLACKBURN, OF DREXEL HILL, PENNSYLVANIA.

FLUE-WALL FACING.

Application filed September 27, 1928. Serial No. 308,840.

This invention relates to flue wall facings and more particularly to an improvement of the structure disclosed in my prior patent for flue wall facings, granted August 18, 5 1925, No. 1,550,143.

As is well known to those familiar with the art, flue walls leading from a fireplace are more or less rough and irregular, particularly as regards the sloping or inclined parts of the flue wall which lead to the chimney and this is true even when the walls are constructed of concrete or material other than brick. As a consequence, the passage for smoke or products of combustion is more or less retarded. This roughness is accentuated in brick constructions, due to the fact that very few of the present day masons are competent to properly build the throat of a fireplace, particularly as respects the sloping walls thereof. Accordingly, an important object of the present invention is the provision of a flue wall facing or lining which covers all sloping faces of the flue wall and which has the advantage of interlocking with the brick-work or other masonry, as set forth in the prior patent above mentioned. It is here pointed out that there are usually three sloping walls in the fireplace throat, two of these walls being the side wall and the third the front wall of the throat.

A further object of the invention is to produce a device including a plate for guiding the construction of the masonry of and lining each of these three walls, wherein the side plates include vertically directed lugs adapted to enter into interstices between adjacent elements of the flue wall and have coaction with the third plate so that this plate is locked and held in position with relation thereto.

These and other objects I attain by the construction shown in the accompanying drawing, wherein for the purpose of illustration is shown a preferred embodiment of

Figure 1 is a front elevation of a chimney having a flue wall facing constructed in accordance with my invention;

Figure 2 is a vertical sectional view on the line 2-2 of Figure 1;

Figure 3 is a perspective view showing the facing plates assembled;

55 Figure 5 is a perspective view of a modified form of front facing plate;

Figure 6 is a perspective view of a further modified form of plate.

In the drawings, 1 designates the chimney generally, 2 the fireplace and 3 the smoke flue which leads upward from the back of the fireplace and which communicates with the vertical and relatively small flue 6 of the chimney. The flue 3 has vertical walls at its lower portion and upwardly and inwardly extending walls above these vertical walls which are directed toward the chimney throat. 60 65

There are two of these sloping or inclined walls on each side of the chimney. 70

In order to cover up the irregularities which usually occur in these walls, I provide flue facing plates or linings 7 which are disposed upon the inner faces of the inclined or sloping walls of the flue. These plates may be of cast iron, terra cotta or any other suitable material. Each facing plate is provided with a marginal reinforcement or thickened portion 8, and projecting laterally from the opposite longitudinal edges thereof are the lower lugs 9 and the upper lugs 10. The lugs 9 are disposed somewhat above the extreme lower edge of the plate 7. These lugs, as shown in Figure 3, are disposed in a normally vertical position, that is, when the plates are disposed within the throat of the chimney, these lugs are vertical and, therefore, are parallel to the vertical joints between the bricks of the chimney. Furthermore, the upper and under faces of these lugs provide shoulders which support the brick work of the chimney. The upper lugs 10 are intended to be disposed practically on a level with the bottom of the chimney throat.

From the upper margin of the plate extends the upwardly projecting lugs. These lugs are also vertical and there are preferably a pair of these lugs, the material of the plate being thickened immediately below these lugs 11 and behind the rib or reinforce 100 8 so as to form shoulder portions 13 which have bolt apertures. Through these apertures pass the transversely extending bolts 15, each of these bolts being screw-threaded at its opposite ends and carrying at each end 105 a pair of nuts 16, between which each plate 7 is adapted to be engaged.

Coacting with the lugs 11 and supporting the lining 17 of the chimney is a base 18 which is formed of metal, terra cotta, or any other suitable material. 110

The front wall of the throat likewise in-

clines inwardly and upwardly and against this front wall, I dispose a plate 19, which may be notched at its edges at points 20 and 21 to receive the lugs 9 and 10 which project from the front edges of the plate 7. These lugs are provided with perforations for the passage of nails 22 or some corresponding securing element. The upper edge of this plate projects above the upper edges of the plate 7 and accordingly above the seat of the base 18 and closes the joint of this base to render the same tight and fire-proof. If desired, the plate 19 may be of slightly greater width than the distance 15 between the edge walls of the chimney when completed, as in Figure 5, in which event, the lugs 9 and 10 at the forward edges of the plates are preferably engaged through the plates at slots 23 formed in the lower 20 edges thereof and openings 24 formed adjacent the upper ends thereof. In a further modification, the side edges of the plate 19 may be provided with a flange 25 for fitting against the outer faces of the coacting plates 25 7 and more particularly against the ribs 8 thereof. These flanges will serve to seal the space between the edges of the plates and prevent passage of flame through this space to contact the walls of the chimney. With 30 either type of plate, the securing element 22 employed may be identical.

It will be obvious that by employing a construction of this character, the front plate may be readily combined with a structure such as shown in my prior patent and may be secured thereto by elements which are readily accessible at any building which is in the process of construction.

It will also be obvious that the construction illustrated is capable of a certain range of change and modification without materially departing from the spirit of the invention and I accordingly do not limit myself to such specific structure except as herein- 45 after claimed.

I claim:—

1. In a flue, a pair of flue wall facing plates disposed in upwardly convergent relation and having at their front and rear edges vertically extending outwardly projecting lugs adapted to engage in interstices of the masonry from which the chimney is formed and a plate abutting the forward edges of the first named plates apertured for the passage of said lugs and adapted to seal the space between adjacent faces of the plates at the forward edge thereof.

2. In a flue, a pair of flue wall facing plates disposed in upwardly convergent relation and having at their front and rear

edges vertically extending outwardly projecting lugs adapted to engage in interstices of the masonry from which the chimney is formed, a plate abutting the forward edges of the first named plates apertured for the 65 passage of said lugs and adapted to seal the space between adjacent faces of the plates at the forward edge thereof, and means for securing the last named plate to the first named plate.

3. In a flue, a pair of flue wall facing plates disposed in upwardly convergent relation and having at their front and rear edges vertically extending outwardly projecting lugs adapted to engage in interstices 75 of the masonry from which the chimney is formed and a plate abutting the forward edges of the first named plates apertured for the passage of said lugs and adapted to seal the space between adjacent faces of the plates at the forward edge thereof, said lugs being apertured for the passage of securing elements outwardly of the outer face of the last named plate.

4. In a flue, a pair of flue wall facing 85 plates disposed in upwardly convergent relation and having at their front and rear edges vertically extending outwardly projecting lugs adapted to engage in interstices of the masonry from which the chimney 90 is formed, a plate abutting the forward edges of the first named plates apertured for the passage of said lugs and adapted to seal the space between adjacent faces of the plates at the forward edge thereof, and a 95 flue supporting base seated upon the upper edges of the first named plate, the last named plate projecting above the upper edges of the first named plates and above the joint between said flue support and the first named 100 plate.

5. In a flue, a pair of flue wall facing plates disposed in upwardly convergent relation and having at their front and rear edges vertically extending outwardly projecting 105 lugs adapted to engage in interstices of the masonry from which the chimney is formed, a plate abutting the forward edges of the first named plates apertured for the passage of said lugs and adapted to seal the space 110 between adjacent faces of the plates at the forward edge thereof, and means for securing the last named plate to the first named plate, said plate at its side edges having flanges for engaging against the outer faces 115 of the first named plate.

In testimony whereof I hereunto affix my signature.

WILLIAM N. BLACKBURN.
